MOLTEN METAL-AIR THERMAL POWER
PLANT

John Forster Alcock, North Lancing, England, assignor, by mesne assignments, to Ricardo & Co. Engineers (1927) Limited, London, England, a company of Great Britain

Application January 13, 1948, Serial No. 1,937
In Great Britain January 23, 1947

7 Claims. (Cl. 60—59)

1 This invention relates to thermal power plants of the type in which the working medium circulates in a closed system in which is included at least one compressor driven by a turbine and one or more heat exchangers in which heat is imparted to or taken from the working medium.

The invention relates more especially to the heat exchangers in such plants and has for its object to obviate the use of those of the surface type in which, for example, heat is transferred from gases of combustion or other like outside source through metal walls to the working medium. In power plants of the above mentioned kind in which heat exchangers of this type have been employed the metal walls of the input heater wherein heat is imparted to the working medium from an outside source, have been subjected internally to the full pressure of the working medium. This has given rise to many problems due to the small difference between the temperature to which the working medium must be heated and the allowable temperature for the tubes of the heat exchanger. This temperature difference, however, must be substantial in order to obtain an adequate heat transfer owing to the low conductivity of the gas constituting the working medium. There is also the danger that owing to an unforeseen local increase in the heat transference, for instance owing to some variation in the heat supply from the outside source, the temperature of some of the tubes in the heat exchanger may rise with an increase of local heat flow far more than in a steam generator. Thus overheating and damage to the tubes or their equivalent may happen with relatively slight provocation.

According to the present invention the heating of the gaseous working medium is effected by a liquid heat-conveying medium which after being heated from an outside source is brought into direct contact with the working medium in the circuit so that heat is transferred directly to the working medium from the liquid heat-conveying medium. The heat-conveying medium employed is for example a molten metal or metal alloy. This heat-conveying medium is preferably heated under a low pressure in a surface heat exchanger outside the closed circuit of the working medium in the power plant into which the liquid heat-conveying medium is then introduced under a substantially higher pressure. After it has given up heat to the working medium the heat-conveying medium is used to take up heat from the exhaust working medium gases leaving a turbine in the plant before the heat-conveying medium is returned for reheating by the outside source. This heating of the heat-conveying medium from an outside source may be effected in various ways as for instance by a fluid flowing in a circuit, this fluid itself being heated

by direct or indirect contact with combustion gases from a suitable source of heat.

The accompanying drawing illustrates diagrammatically and by way of example a hot gas turbine power plant in which the present invention is embodied.

In the construction shown the working medium may be, for instance, nitrogen and the heat-conveying medium, for example, may be molten gallium, and in the following description will be referred to as that metal.

The gallium is contained in a coil of piping A enclosed in a casing B and the coil is heated, for example, by combustion of fuel in a burner C. Air enters the casing B through a passage B¹ and the hot gases after passing over the coil issue at B². Conveniently the entering air and the issuing hot gases are caused to pass through a heat exchanger D which, may be of the rotary type wherein the hot gases pass through a matrix of heat-conducting material to which heat is given up, the heat being subsequently given out to the air entering at B¹ as it passes in the opposite direction through the matrix material in the exchanger D.

The molten gallium from the coil A is delivered by a pump A¹ through a suitable nozzle A² in the form of a spray which is directed downwards into a chamber E which in effect functions as a scrubber and for convenience may be referred to as the gas-heating scrubber. The nitrogen delivered by a compressor F driven by the gas turbine G is delivered through the piping H into the lower part of the scrubber E wherein this gas passes upwards and is met by the downwardly directed spray of molten gallium from the jet nozzle A².

From the upper part of the scrubber E the heated gas passes through piping E¹ into a separator J wherein is removed any metal spray that may be carried over from the scrubber E. The molten metal thus removed drains back through the piping E² into the scrubber E and falls to the bottom where it is collected the molten metal delivered into the scrubber from the jet nozzle A².

The nitrogen coming from the compressor F, which has been heated in the scrubber E is under a substantial pressure and is led through piping K to the turbine G which is driven by this gas, the turbine in turn, as already mentioned, driving the compressor F.

There is a second scrubber L, which for convenience may be referred to as the gas-cooling scrubber. The nitrogen after imparting rotation to the turbine G is led through piping L¹ into the lower part of the scrubber L wherein the gas flows upwardly and is met by a downwardly directed spray of molten gallium issuing through a nozzle M to which is delivered through piping E³, for example by gravity the molten metal

3

which has accumulated at the bottom of the gas-heating scrubber E. This molten gallium is at a lower temperature than the temperature of the nitrogen which enters the gas-cooling scrubber L so that the gas is cooled by the gallium spray. The nitrogen partly cooled by the gallium in the gas-cooling scrubber L is led by way of a pipe M¹ into a heat exchanger N through which water passes, the water entering at O and issuing at O¹. The temperature of the nitrogen is further reduced in the heat exchanger N so as to bring this temperature down to the lowest practicable value before the gas flows through the piping N¹ to the compressor F.

The molten gallium from the jet nozzle M is collected at the bottom of the gas-cooling scrubber L and taken thence through piping L² to the upper end of the coil A wherein the gallium is again heated.

In the above described apparatus it will be apparent that the input heater A, B wherein the gallium or other heat-conveying medium is heated functions with the gas-heating scrubber E as the equivalent of a surface heat exchanger, such as is commonly employed in known plants of this type, for the purpose of effecting the initial heating of the working medium from an outside source. The lower part of the gas-heating scrubber E where the heat-conveying medium collects functions in combination with the gas-cooling scrubber L as a regenerator. If desirable the functions of the gas-heating scrubber E may be divided between two scrubbers in one of which the gas meets the heat-conveying medium from the input heater A, B while in the other the gas meets the liquid from the gas-cooling scrubber L.

The advantages of a thermal power plant according to the present invention may be summed up as follows. The heat transfer coefficient from the heating surface of the input heater A, B to the liquid heat-conveying medium such as gallium, is so much greater than the gas-tube coefficient in the surface type input heaters employed in known thermal power plants operating on a gaseous medium, that the tube or wall temperature will be practically that of the liquid heat-conveying medium. Consequently accidental local over-heating of the metal walls will have comparatively little effect on the temperature of these walls. This immunity from over-heating enables the heating surfaces of the input heater A to be reduced by making full use of radiation from the products of combustion from the jet nozzle C. Since in the coil A of the input heater the heat-conveying medium is heated at low pressure, as compared with the pressure of upwards of 20 atmospheres in known thermal plants using a gaseous medium, the metal in the heater is only slightly stressed.

The use of scrubbers such as E and L provides in a small space a large surface for heat transfer between the liquid heat-conveying medium and the gaseous working medium. The operation of the scrubbers is facilitated by the fact that the possible liquids which may be employed are generally of high density, a fact which increases the permissible through-put for a given scrubber tower. The scrubbers replace the normal exhaust-to-compressed gas heat exchanger, as well as the input gas heater. Apart from the input heater A the only tubular or plate surface heat exchangers retained in the present system are the water-cooled heat exchanger N and any intercooler which it may be desirable to employ, and these may be small low temperature units.

4

In the type of regenerator described the liquid heat-conveying medium moves in contraflow to the gas stream in each scrubber, and each part of the heat-conveying medium swings during the cycle over a temperature range nearly equal to that of the gas which is being heated or cooled. Thus what may be referred to as the "matrix flow rate" is far less than in the normal regenerator where the matrix material in effect "flows" across the gas stream and for efficient operation can only be allowed to swing through a small temperature range. In other words, the quantity of liquid to be pumped is small and there is obviously no blow-down loss with this type of regenerator. Reheating can be effected easily by feeding part of the hot liquid to a second scrubber between high pressure and low pressure turbines when these are employed.

In addition to these advantages the system forming the subject of the present invention retains those which are inherent to the closed cycle air turbine power plant.

With regard to the liquid heat-conveying medium, generally speaking the requirements are as follows but it is to be understood that in some cases it is practicable to use a liquid heat-conveying medium which does not fulfill all these requirements.

(1) It shall not attack the metal of the input heater up to temperatures of the order of 750° C.

(2) It shall not decompose up to a temperature of the order of 750° C.

(3) It shall have no reaction with the working fluid, which is preferably nitrogen.

(4) It shall have a low melting-point, preferably of the order of 75° C. or less for reasonable ease in starting up the plant. This upper limit to the melting point is desirable to allow for "thawing" the system by the aid of steam after a shut-down of the plant.

(5) The medium must not be inflammable or toxic.

(6) It is desirable that the liquid shall have a high boiling-point to minimise vapour carry-over. A boiling-point of the order of 900° C. or over is desirable.

(7) A high thermal conductivity is desirable.

(8) A high density is desirable to facilitate scrubbing and spray separation.

Possible materials for employment in a plant of this nature are: (a) metals, (b) salts. Among the metals is Gallium metal, its advantages being:

Melting point of the order of 30° C.

Boiling point of the order of 1800° C.

Density about 6.

Tendency to oxidize, low.

Other possibilities are metal alloys, for example, fusible alloys similar to Wood's metal. Again, alkali metals, notably sodium and potassium, may be used since these have the advantage of a low cost and that they do not attack ferrous metals. Alloys of these two metals have suitable melting points and for example an alloy which may be used may contain 50% to 60% of sodium with 50% to 40% potassium and having a melting point about 20° C. Though a sodium potassium alloy does not actually fulfill all the above mentioned requirements, on the other hand such an alloy may be employed. It is undesirable to employ fusible metal alloys containing mercury owing to its volatility, or those with a high bismuth content owing to expansion on solidification with consequent risk.

of pipe fractures if the plant is allowed to cool off.

If a substance is employed which expands on freezing the ill-effects of the expansion may be avoided, for example, by either of two methods:

(a) The insertion into the pipes of an inner flattened pipe of thin metal which can absorb the expansion without over-stressing the main pipe or permanently deforming the flattened pipe. In cases where such an inner pipe is employed it may also serve to carry steam for the purpose of "thawing" the plant in the event of a shut-down.

(b) The provision in the plant of means by which all the metal forming the liquid heat-conveying medium may be drained into a sump provided with steam heating coils to enable it to be re-melted on restarting the plant.

With regard to the gaseous working fluid, air is undesirable owing to its liability to cause oxidation of the liquid heat-conveying medium and/or the metal walls of scrubbers and pipe work. Argon would be suitable, but is hardly practicable owing to its cost, as a certain amount of leakage of the working fluid would be inevitable. Nitrogen which is readily provided is a suitable and convenient gas.

What I claim as my invention and desire to secure by Letters Patent is:

1. A thermal power plant comprising in combination a working fluid circuit containing a gaseous working medium and including in the circuit a compressor, a turbine which drives the compressor, a delivery passage between the outlet of the compressor and the inlet of the turbine including a first heat exchanger, a return flow passage between the outlet of the turbine and the inlet of the compressor and including a second heat exchanger through which the gaseous working medium passes after leaving the turbine and a third heat exchanger through which the working medium passes after passing through the second heat exchanger, means for passing a cooling fluid through the third heat exchanger to cool the working medium passing therethrough, and a heat-transfer-liquid circuit in which flows a liquid heat-conveying medium including the first heat exchanger through which the heat-conveying-liquid flows in the opposite direction to the flow of gaseous working medium therethrough whereby the gaseous working medium leaves the said first heat exchanger at a temperature higher than the heat-conveying-liquid leaves the said first heat exchanger, the said second heat exchanger through which the heat-conveying liquid flows in a direction opposite to the working medium flowing therethrough, and a liquid-heating device deriving heat from a source external to the circuits and through which the heat-conveying liquid passes on its way from the second heat exchanger back to the first heat exchanger, the drop in temperature of the working medium in its passage through the turbine being less than the difference between the temperatures respectively of the working medium and of the heat-conveying liquid leaving the first heat exchanger.

2. A thermal power plant as claimed in claim 1 in which each of the first and second heat exchangers comprises a scrubber operating as a heat exchanger in which heat is transferred between the heat-conveying liquid and the gaseous working medium by direct contact while the liquid and the medium are flowing in opposite directions through the scrubber.

3. A thermal power plant as claimed in claim 2, in which the heat-conveying liquid is heated by the heating device while the said liquid is at a relatively low pressure and means are provided for raising the pressure of the heat-conveying liquid after it has been so heated and causing it to flow at a substantially higher pressure into the first heat-exchanger.

4. A thermal power plant as claimed in claim 10 3, in which the heat-conveying liquid is a molten metallic mass.

5. A thermal power plant as claimed in claim 15 1, in which the heat-conveying liquid passes at relatively low pressure through the heating device and means are provided for raising the pressure of the heat-conveying liquid and causing it to flow into the first heat-exchanger at a substantially higher pressure than that at which it is heated in the heating device.

6. A thermal power plant as claimed in claim 20 5, in which the heat-conveying liquid is a molten metallic mass.

7. A thermal power plant comprising in combination a circuit containing a gaseous working medium and including in the circuit a compressor by which the gaseous medium is caused to flow round the circuit, a turbine which drives the compressor, a delivery passage connecting the compressor outlet to the turbine inlet and including a first scrubber operating as a heat-exchanger through which the working medium passes before it acts on the turbine, a second scrubber operating as a heat-exchanger through which the working medium passes after it has passed through the turbine, a return flow passage between the turbine outlet and the compressor inlet including a surface heat-exchanger through which the gaseous medium passes and in which it is cooled after leaving the second scrubber and before it again enters the compressor, a liquid heat-conveying medium circuit including the first scrubber through which the heat conveying liquid is caused to flow in an opposite direction to and in direct contact with the gaseous working medium, the second scrubber through which the heat-conveying liquid flows after leaving the first scrubber and in a direction opposite to and in direct contact with the gaseous working medium, a surface heat-exchanger through which the heat-conveying liquid flows after leaving the second scrubber and in which heat is imparted to it from an external source of heat while the heat-conveying liquid is at a relatively low pressure, and a pump operative on the heat-conveying liquid when it leaves the said surface heat-exchanger, for delivering it to the first scrubber, the temperature drop of the working medium in passing through the turbine being less than the difference in the temperatures respectively of the heat-conveying liquid and the working medium leaving the first scrubber.
